(57) **CLAIM**

The ornamental design for a funeral memorial book flower card holder, as shown and described.

DESCRIPTION

FIG. 1 is a perspective view of a funeral memorial book flower card holder of the present invention;

FIG. 2 is a front elevational view, the rear elevational view being a mirror image, of the funeral memorial book flower card holder of the present invention;

FIG. 3 is a top view of the funeral memorial book flower card holder of the present invention;

FIG. 4 is a bottom plan view of the funeral memorial book flower card holder of the present invention;

FIG. 5 is a right side elevational view of the funeral memorial book flower card holder of the present invention; and,

FIG. 6 is a left side elevational view of the funeral memorial book flower card holder of the present invention.

The cards in the pockets and holes in the left margin depicted by means of broken lines in FIGS. 1 and 3 have been shown for illustrative purposes only and form no part of the claimed design.
